CHARLES F. NEILEY, OF PORT WASHINGTON, NEW YORK, ASSIGNOR TO AMERICAN CIGAR COMPANY, OF NEW YORK, N. Y., A CORPORATION OF NEW JERSEY

DISPLAY DEVICE

Application filed August 10, 1929. Serial No. 384,995.

This invention is an improvement in display devices, and more particularly in a device for displaying packaged goods, such as cigars in boxes.

5 In order to display boxed cigars, the lid or cover is opened, and since said lid or cover usually carries display matter relating to the cigar, it is desirable that the lid be supported in a position such that the display matter of 10 the lid be in somewhat near the same plane as the topmost layer of cigars, that is, in a position such that a single glance may take in both display matter and cigars.

It is also desirable that for convenience of 15 observation, the box and the cover be upon a plane inclined to the horizontal, so as to bring the display more nearly at right angles to the line of vision.

One of the primary objects of the present 20 invention is the provision of a simple and relatively inexpensive support for holding one or more boxes of cigars in the desired position, that is, with the plane of the topmost layers of the cigars substantially perpendicular to the line of vision, and with the display matter of at least one lid in substantially the 25 same plane as the topmost layer of cigars.

Another object is the provision of a device 30 of the character in question, wherein the lid of one or more boxes is utilized as an easel supporting means for the device, to hold it in a position such that the plane of the topmost layer of cigars is substantially perpendicular to the line of vision.

35 Another object is the provision of a device so constructed and arranged as to occupy a minimum of room, and to support a plurality of boxes of cigars in a minimum of space.

Another object is the provision of a device 40 of a nature such that it may be shipped with boxes of cigars packed therein, without requiring greater room than the boxes which it contains.

Another object is the provision of a device 45 in the form of a box for containing a plurality of boxes of cigars of a nature such that when received by the retailer, it may be quickly and easily converted into an easel support by utilizing the covers of sundry of 50 the boxes in a specified manner.

With these and other objects in view the invention consists in the construction and novel combination of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:—

Fig. 1 is a perspective view of the improved device with a single box of cigars in place, and in display position.

Fig. 2 is a transverse vertical section of the device, with the boxes shown in dotted lines.

Fig. 3 is a top plan view of one embodiment of the invention.

In the embodiment of the invention shown in the drawings, the device consists of a substantially rectangular frame 1, formed from suitable sheet material, as for instance, sheet metal. As shown in Fig. 3, the frame is composed of two similar sections, each including a side and an end, the adjacent sides and ends of the sections being seamed together, as shown at 2.

Each of the sections of the frame has at its lower edge an inwardly extending ledge or shoulder 4, the arrangement being such that this ledge or shoulder is continuous when the sections of the frame are connected. The frame is of a depth corresponding to the depth of a cigar box, and of a width corresponding to the length of the box. The length of the frame is twice the width of a cigar box, so that two boxes may be inserted in the frame, resting on the ledge or shoulder 4, as indicated in Fig. 2.

At the center of the sides of the frame, the ledge 4 is notched, as shown at 5, the notches being in register transversely of the frame, and of a width corresponding substantially to the thickness of the lid 6 of the cigar box indicated at 7. The cigars shown at 8 are arranged in the box in the usual manner, and the frame is so proportioned with respect to the box, that the topmost layer of cigars will

be at the level of the upper edges of the frame walls.

A plate 9 is secured to one of the end walls of the frame in any suitable manner, the said plate being angular in cross section, composed of two parts extending at an obtuse angle with respect to each other. One of these parts is secured to the frame, as shown at 10 in Fig. 2, and the other part, which extends at an obtuse angle to the plane of the top frame, is for a purpose to be presently described. In use, a box of cigars is arranged in the frame, as indicated in Fig. 1, the lid being turned back upon the adjacent side of the box, and pushed down through the notches 5 of the frame, until the box seats upon the ledge or shoulder 4. The other box, the frame as before stated, being adapted to support a plurality of boxes, is arranged between the first named box and the plate 9. The lid of the second box is fully opened, and rests against the support 9, the lid of the first box serving as an easel support to hold the frame with the cigar boxes in the position shown in Fig. 2.

It will be apparent from the description that the boxes are so supported that the top-most layers of cigars are in the same plane, and in a plane substantially perpendicular to the line of vision of an observer standing in front of the device arranged at a level somewhat below the eye of the observer. It will also be apparent that the lid of the box adjacent the plate 9 will be held inclined, and in a position such that it may be seen simultaneously with the cigars in the boxes. While the device in the present instance is shown as an open frame having the ledge 4 notched to receive the lid, it will be apparent that the support might be an open or lidless box, with a transverse slot through which the lid 6 might pass.

While the device is shown as embodied in mechanism for holding two boxes of cigars, it is apparent that the same principle may be used for supporting a single box, merely by making the frame of the proper size to embrace the single box. Or it might also be used for supporting a plurality of pairs of boxes, or for supporting a plurality of single boxes arranged end to end. Furthermore, with a pair of boxes, or with a plurality of pairs, the lid of either the upper or lower box or row of boxes might be used to support the device.

The invention consists in providing a frame or other means to embrace a box or boxes in the manner set forth, and a passageway through which the lids of certain boxes may pass when arranged in the position specified, to extend below the support, to support the same and the boxes in inclined position. That is, the support utilizes the box lids of certain of the boxes for supporting the same.

What is claimed as new is:—

1. A device of the class described, including a frame for embracing a cigar box, and having means cooperating with the frame to hold the lid of the box turned down parallel with the side wall thereof, thereby to extend below the bottom of the frame to serve as an easel support for holding the box and frame in inclined position. 70

2. A device of the class described, including a frame for embracing a cigar box and having means to support the box, and having a passageway for the lid when it is turned down parallel with the side wall of the box to enable it to extend below the bottom of the frame to serve as an easel support to hold the box and frame in inclined position. 75 80

3. A device of the class described, including a frame for embracing a pair of cigar boxes similarly arranged alongside one another with their long axes parallel, and having means cooperating with the frame to hold the lid of one box of the pair turned down parallel with the side wall thereof, thereby to extend below the bottom of the frame to 90 serve as an easel support for holding the boxes and frame in inclined position. 90

4. A device of the class described, including an open top holder of a size to receive a pair of cigar boxes similarly arranged alongside one another with their long axes parallel, and with the lid of one box turned down between the boxes, said holder having means to enable the passage of said lid below the bottom of the holder to serve as an easel support for the holder. 95 100

5. A device of the class described, including an open top holder of a size to receive a pair of cigar boxes similarly arranged alongside one another with their long axes parallel, and with the lid of one box turned down between the boxes, said holder having means to enable the passage of said lid below the bottom of the holder to serve as an easel support for the holder, and having means to support the boxes with their tops substantially level with the top of the holder. 105 110

6. A display device to hold a pair of similarly arranged cigar boxes with their long axes parallel and with the lid of one box turned down between the boxes, including a frame embracing the boxes and having a support for the bottoms thereof to hold the boxes with their tops at the level of the frame top, said support having a passageway through which the turned down lid extends to enable said lid to serve as an easel support for the device. 115 120

7. A display device to hold a pair of similarly arranged cigar boxes with their long axes parallel and with the lid of one box turned down between the boxes, including a frame embracing the boxes and having a support for the bottoms thereof, said support having a passageway through which the 125 130

turned down lid extends to enable said lid to serve as an easel support for the device, the frame having a support for the lid of the other box to hold it inclined at an obtuse angle to the plane of the box tops.

5 8. A device of the class described, including a frame for embracing pairs of similarly arranged cigar boxes, and for holding them at the same level with the members of each 10 pair having their long axes parallel, the frame having means cooperating therewith and between the members of the pairs for holding the lid of one box of each pair turned down parallel with the side wall thereof, and extending below the bottom of the frame 15 to serve as an easel support for holding the boxes and frame in inclined position.

Signed at New York, N. Y. in the county of New York and State of New York this 20 8 day of August, A. D. 29.
